UNITED STATES PATENT OFFICE.

MARCUS A. ERICKSON, OF MINNEAPOLIS, MINNESOTA.

DOUBLE-ACTING SPRING-HINGE.

No. 927,340.

Specification of Letters Patent. Patented July 6, 1909.

Application filed May 23, 1908. Serial No. 434,648.

To all whom it may concern:

Be it known that I, MARCUS A. ERICKSON, of Minneapolis, Hennepin county, Minnesota, have invented certain new and useful Improvements in Double - Acting Spring-Hinges, of which the following is a specification.

My invention relates to hinges designed for use on double acting doors, and the object of the invention is to improve the hinge shown and described in a certain pending application for Letters Patent of the United States filed by me December 19, 1907, Serial No. 407,108.

The invention consists generally in a double-acting hinge having a one piece frame.

Further, the invention consists in means whereby the door may be swung out or lined up from one side, thus avoiding the necessity of passing from one side to the other of the door during the centering operation.

Further, the invention consists in stop devices for limiting the swinging movement of the door.

Further, the invention consists in various constructions and combinations, all as hereinafter described and particularly pointed out in the claims.

In the accompanying drawings forming part of this specification, Figure 1 is an elevation with the side plate at the bottom of the door removed. Fig. 2 is a horizontal sectional view on the line x-x of Fig. 1 showing the normal position of the hinge mechanism. Fig. 3 is a similar view illustrating the position assumed by the mechanism when the door is open. Fig. 4 is a rear elevation illustrating the position of the finish plate in the rear of the hinge and covering the joint of the side plates. Fig. 5 is a detail view showing the position assumed by the cam plate when the door is pushed beyond the normal stopping point. Figs. 6 and 7 are details illustrating the construction of the frame at the end of the hinge. Fig. 8 is a detail view showing the safety stop to prevent the door from swinging beyond the center of the second axis of the cam plate.

In the drawing, 2 represents a double swinging door, 3 a base plate secured to the floor, and 4 the usual pivotal connection between the top of the door and its casing. The lower rear portion of the door 2 has a re-

cess 5 formed therein to receive the frame of the hinge. This frame for convenience of construction and durability I prefer to make in one piece consisting of a bottom portion 6 having a turned up end 7 secured to the rear edge of the door by screws 8 through a finish plate 9. At the other end of the frame the bottom part 6 has a vertical extension 10 terminating in a backwardly extending portion 11 that is parallel with the part 6 and has a tongue formed on its end fitting within an opening in the end 7 and riveted or otherwise secured therein. A tongue 12 is pressed or punched out of the part 10 and turned down into the plane of the plate 6 and is secured to the lower edge of the door by a screw 13. A post 14 has its ends riveted in the plates 6 and 11 and fits within a slot 15 in a bolt 16. This bolt has a threaded portion 17 and an adjusting nut 18 thereon between which and the post 14 a coiled spring 19 is arranged and adapted to be put under compression by the oscillation of said bolt, the degree of compression being regulated by the adjustment of the nut 18. A cam plate 19' is mounted on the end of the bolt 16 and has a central recess 20 to receive a pivot pin 21, and smaller recesses 22 on each side of the middle to receive bearings 23 on a plate 24 that is journaled on the pin 21. This plate has recesses 25 in the rear of the bearings 23 to receive the rounded surfaces of bearing lugs 26 formed on the cam plate 19' on the outer side of the recesses 22. A rearwardly extending arm 27 is provided on the plate 24 and an adjusting screw 28 is mounted in a fixed casting 29 secured to the pin 21 and projects through a threaded hole in the arm 27. A screw 30 is mounted in the casting 29 and bears on the arm 27. By the adjustment of these screws the plate 24 may be swung in either direction and the door centered in the opening without the necessity of passing from one side to the other of the door to perform the adjusting operation. The workman having his screw driver at hand can center the door from one side without changing his position.

When the door is swung open the bearing of the cam plate will be on one of the bearings 23 until the door has moved to a point past the center, when it may be released and will stay in an open position. It may also be pushed still farther open, swinging on the

bearing lugs 26 until one of the shoulders 31 on the casting 29 is engaged by the stop 32 on the part 6 of the frame. When the door has been pushed back against one of these 5 stops and is released it will close automatically the momentum of the door and the tension of the spring being sufficient to swing the door past the center of its bearing or its normal position when open.

10 I prefer to provide a ball bearing between the upper end of the pin 21 and the door, comprising rings 33 and 34 with balls 35 between them, the ring 33 having a flange fitting within a socket 36 in the part 11 of the 15 frame. This construction enables me to locate the ball bearing above the floor where it is less exposed to the accumulation of dust and dirt. The casing for the hinge consists 20 preferably of plates 37 secured to the turned up end 7 of the frame, and having the joint between them concealed by the finish plate 9. The opposite ends of the plates 37 are 25 provided with inwardly projecting hook portions 38 which engage the part 10 on each side of the opening formed by the tongue 12, and are held in place thereby. In this way 30 no screws will be visible on the side of the hinge to mar the finished appearance.

When the door is opened and the bearings 35 of the cam plate transferred the coiled spring will be put under compression, the bolt 16 sliding on the bolt 14 which serves not only to hold the bolt in place but as a guide during the sliding movement.

35 I claim as my invention:

1. In a double acting spring hinge, a frame having an upwardly turned part adapted to be secured to the rear edge of the door, and a horizontal bottom part in line substantially 40 with the lower edge of the door, the inner end of said bottom part being upwardly turned and terminating in a rearwardly extending part that is rigidly secured to said upwardly turned end, and the upwardly 45 turned portion of the forward end of said bottom part having a tongue pressed or punched therefrom for securing said frame to the door, substantially as described.

2. In a double-acting spring hinge, means 50 capable of adjustment on one side of the door for centering it when closed, said means including adjusting screws and a plate having a threaded hole to receive one of said screws and a surface to contact with the other screw, 55 substantially as described.

3. In a double acting spring hinge, a pivot pin, a casting secured thereon, adjusting screws mounted in said casting, a plate journaled on said pin and having a threaded hole 60 to receive one of said screws, and a surface to contact with the other screw, whereby the movement of one screw will draw said plate in one direction and movement of the other

screw will push it in the opposite direction, 65 for the purpose specified.

4. In a double-acting spring hinge, a pivot pin, a plate journaled thereon having bearing lugs on each side of said pin and recesses on each side in the rear of said lugs, a sliding 70 bolt, a spring thereon, and means for regulating its tension, a cam plate carried by said bolt and having recesses on each side of its center to receive the bearing lugs on said first-named plate and said cam plate also 75 having bearing lugs, which are adapted to enter the recesses in the rear of the bearing lugs on said first named plate and form secondary bearings, and being effective only when the door is swung beyond a predetermined point in either direction, substantially 80 as described.

5. In a double acting spring hinge, the combination with a frame, of a slotted bolt therein, a spring coiled thereon, a cam plate 85 mounted on one end of said bolt and having lugs on each side thereof and recesses between said lugs and a bearing having lugs to enter said recesses and on which said bolt and the door normally turn, and said bearing 90 having recesses in the rear of its lugs to receive the lugs on said cam plate and thereby form a secondary bearing, said lugs becoming effective only when the door approaches the limit of its open position, substantially as 95 described.

6. In a double acting spring hinge, a frame comprising upper and lower plates adapted to fit within a recess in the lower edge of the door, said lower plate having a stop formed 100 thereon, a pivot pin, a casting secured thereto and shoulders provided on said casting and adapted to contact with said stop, substantially as described.

7. In a double-acting spring hinge, the 105 combination with a frame, of a bolt, a spring coiled thereon, a cam plate mounted on one end of said bolt and having double bearings on each side of the center thereof, a stationary part arranged to contact with said cam 110 plate and engage its bearings on either side successively, one bearing on either side between said plate and part being effective during the initial opening of the door in either direction and the other bearing on either side 115 being effective only during the final movement of the door toward an open position, said final movement separating the parts forming the initial bearing, substantially as described.

120 In witness whereof, I have hereunto set my hand this 16th day of May 1908.

MARCUS A. ERICKSON
